TAPE DISPENSER

Irvin J. Gershen, 1 Norwood Road, Springfield, N.J.

Filed Oct. 20, 1959, Ser. No. 57,980

Term of patent 14 years

(Cl. D74—1)

Fig. 1 is a front perspective view of a tape dispenser showing my new design;

Fig. 2 is a similar view thereof as it appears with the bridge in open position;

Fig. 3 is an end elevational view as seen from the left of Fig. 4;

Fig. 4 is a side elevational view;

Fig. 5 is an end elevational view as seen from the right of Fig. 4; and

Fig. 6 is a top plan view thereof.

The side of the dispenser opposite to that shown in Figs. 1, 2 and 4 is identical in appearance with that shown in Fig. 4 with the single exception that the three snap fittings which appear in Figs. 1, 2, 3, 5 and 6 would

appear on this side and do not appear on the side shown in Fig. 4.

I claim:

The ornamental design for a tape dispenser, substantially as shown and described.
